Application May 9, 1932, Serial No. 610,126
In Great Britain May 20, 1931

1 Claim. (Cl. 178—6)

This invention relates to television and like apparatus and more particularly to scanning apparatus for use in television and like systems.

The invention has for its object to provide an improved scanning system wherein certain practical limitations met with in most known systems are avoided.

In the specification accompanying copending application Serial No. 592,513, filed February 12, 1932, there is disclosed a television scanning apparatus comprising a first driven member having thereon a plurality of elementary areas adapted to follow one another through the same path and a second driven member associated with said first member and having thereon deflecting means adapted to follow one another through a path having an angular relationship to the path of the elementary areas on the said first member, the relative speeds and arrangement of said members being such that the picture surface to be scanned is explored in a series of parallel lines each due to the movement of an elementary area on the first member through the effective portion of its path, said lines being spaced from one another by distances due to the deflection set up by the movement of the second member.

An examination of this system will show that, as is the case with many other systems, practical limitations impose themselves when high speeds and fine scanning are desired. Take the case of a picture of a given area scanned a number of times per second by a light spot of the usual square section then the linear dimensions of the scanning light spot must be inversely proportional to the number of scanning lines per picture, and the ratio of the linear dimensions of the spot to the length of the scanning lines is also inversely proportional to this number of scanning lines. This ratio is the same as the aperture ratio i. e. the ratio of the aperture dimensions on the light projecting drum to the distance between the apertures.

It will be seen therefore that having given a certain speed of the scanning drum an increase in the number of scanning lines per picture, i. e., an increase in the fineness of scanning will involve an increase in the number of apertures, an increase in the drum diameter and a decrease in the aperture ratio, and if the change in the last factor is obtained by decreasing the aperture dimensions there is soon found to be a practical limit determined by the minimum aperture area necessary to provide a light beam of sufficient intensity to actuate photo-electric cells satisfactorily.

This minimum size depends upon the light source available and for light sources such as are now ordinarily employed in practice the minimum size is about 0.5 mm. square. If the aperture dimensions be assumed fixed say at this minimum

value a further increase in the fineness of scanning involves a proportional greater increase in the drum diameter and here again practical limits impose themselves and for a drum running at 750 R. P. M. the practical mechanical limit is reached with a drum diameter of about 1 metre, the practical mechanical limit being reached at smaller diameters with higher speeds. As an extreme practical example of these difficulties, a picture 24" x 24" scanned by 200 lines 12.5 times per second would require an aperture drum of about 25" diameter having 20 apertures each 0.5 mm. square, said drum running at a speed of 7,500 R. P. M.

The inter-relationship above referred to will be better understood from the following quantitative analysis. Suppose the picture area to be scanned is of length l and breadth b and suppose it is to be scanned by a combination of apertured drum and mirror wheel at right angles to one another as are the lens drum and mirror wheel of Figure 1 to be described later. Let the size of the apertures be a_1 square the distance between two adjacent apertures b_1 and the number of scanning lines n . Then the size of the spot on the screen is

$$\frac{l}{n}$$

if the scanning spot moves parallel to the side of length b . Hence b_1 on the drum is magnified to b on the screen. Therefore b divided by

$$\frac{l}{n}$$

equals

$$\frac{b_1}{a_1}$$

i. e.,

$$\frac{nb}{l} = \frac{b_1}{a_1}$$

Let

$$\frac{b}{l} = k,$$

where k is a constant generally lying between $\frac{1}{2}$ and 2. Then

$$\frac{b_1}{a_1} = kn.$$

For n to be large

$$\frac{b_1}{a_1}$$

must be large, i. e. b_1 must be large or a_1 must be small.

Since b_1 is directly proportional to the diameter of the drum, n can only be increased by increasing the diameter or decreasing the aperture.

As above stated, mechanical considerations set a limit beyond which the diameter cannot be increased, this limit being of the order of 1 meter for ordinary slow running drums, the said limit becoming, of course, smaller as the rate of rotation of the drum is increased.

10 Mechanical and optical considerations also impose a limit below which a_1 cannot be decreased, this limit being of the order of .5 mm.

15 The present invention provides an arrangement whereby the apparent size of the apertures can be reduced so that the mechanical and optical limits above mentioned are not reached.

20 To put the matter in another way, the present invention avoids the above mentioned practical limits opposing an increase in scanning speed or fineness of scanning, this result being achieved by substituting for the apertures in the drum or other actual scanning member one or more apertures in association with the lenses of a lens wheel, so that in effect the apparent size of an 25 aperture is substituted for the real size thereof as the determining factor in the scanning system.

25 The invention is illustrated in the accompanying drawing in which Figure 1 shows one form of the invention using a fixed aperture, lens drum, 30 and rotating mirror, and Figure 2 shows a modification in which a movable aperture and lens drum is substituted for the fixed aperture movable lens drum of Figure 1.

35 Referring to Figure 1 which shows schematically one way of carrying the invention into effect a television scanning system comprises a lantern or other convenient screened source 1 of light (the screen is not shown) the light from which is reflected by a mirror 2 and focussed and concentrated by any suitable lens system 3 40 upon a single aperture 4 in a fixed diaphragm or apertured member 5. Light passing through this aperture is projected upon a fixed prism or mirror 6 mounted behind the rim of a lens wheel 45 7, the beam of light incident upon said prism or mirror being substantially parallel to the axis of the lens wheel, and being reflected by said prism or mirror radially outwards with respect to the said wheel, so as to pass through a 50 lens 7' carried by said wheel. The light passing through the lens is projected upon the mirrors of an ordinary scanning mirror wheel 8, whence it is reflected as a scanning spot 9 upon a screen 10. The beam of light incident upon the lens 55 wheel 7 covers two of the lenses 7' on the lens wheel. The axis of rotation of the lens wheel 7 is at right angles to the axis of rotation of the mirror wheel 8, the lens wheel thus providing one component (the high speed component) of 60 scanning and the mirror wheel the other component of scanning.

65 In order to avoid two spots of light appearing on the screen at one time (due to the fact that the beam of light incident upon the wheel will 70 cover two lenses) a gate or equivalent device (not shown) may be provided, the arrangement being such that as one spot leaves the screen another appears thereon.

75 The arrangement in which light from the aperture covers two lenses 7' on the lens wheel 7 has the advantage that throughout the effective traverse of the light the spot upon the screen will be of substantially constant intensity. It will be seen that with the arrangement described, since the spot upon the screen is determined by

what may be termed the apparent size of the aperture, the lens wheel may be of relatively small size, and the lenses thereon may be much closer together than the apertures on an apertured drum could be.

Obviously, if desired, the single aperture 4 in the fixed plate 5 may be replaced by a plurality of apertures which move with the lenses 7' in the lens wheel 7 so that, from the optical point of view, the moving apertures are equivalent to the single fixed aperture of Figure 1. An arrangement of this kind is schematically illustrated in Figure 2 which shows part of a combined apertured and lens drum. In Figure 2, 1 is a source of light which is arranged within a 15 combined apertured and lens drum as shown, the said combined drum consisting of two concentric drum elements moving together the inner drum element having apertures 4' and the outer drum element having lenses 9', the apertures and lenses 20 being so arranged that the center line of a beam of light from the source 1 through an aperture 4' will pass radially through the center of a corresponding lens 7'. In Figure 2 an operative beam of light is shown in chain lines, the dotted lines representing radii passing through the series of apertures 4' and lenses 7'.

25 It is to be understood that the emergent (operative) beam of light shown in chain lines falls upon a mirror wheel such as the wheel 8 of Figure 1 whence it is reflected upon the television screen.

For a better understanding of the invention a quantitative example with reference to Figure 2 will now be given.

30 Suppose it is desired to scan a picture surface in 200 lines.

35 200 apertures 4' equally spaced from one another are punched or otherwise formed in the inner drum of the composite drum structure while the outer drum is provided with 200 corresponding lenses 7'. Then if l_1 is the radial distance between the inner and outer drum elements, l_2 the distance between the outer drum element and the picture and f the focal length of a lens in the outer drum element, the apparent size of the scanning spots 40 on the picture will be a function of l_1 , l_2 , and f while the dimension b (breadth) of the picture will be a function only of l_2 and the separation of the apertures 4' in the drum can be made large by increasing l_2 while still keeping l_1 small. The 45 speed of the drum structure may be maintained small, and in the above specific case may be made equal to the picture frequency of 750 R. P. M.

50 Having now described our invention, what we claim and desire to secure by Letters Patent is the 55 following:

55 In a television system wherein a picture area is scanned by a moving spot of light, a scanning device comprising a rotary lens wheel supporting a plurality of lens elements, a source of scanning rays, a second rotary member arranged concentrically with the first rotary member and having upon the periphery thereof a number of apertures equal to the number of scanning lenses, said lenses and apertures being so associated that the 60 apparent size of an aperture is substituted for the real size thereof as the determining factor in the scanning system, and a mirror wheel rotating about the axis perpendicular to the axis of the lens carrying element for reflecting the light received therefrom over the picture area to be 65 scanned.
